FIG. 1

2,864,563

WINDING APPARATUS

Erwin Sintermann, Unna, Germany

Application January 11, 1957, Serial No. 633,558

10 Claims. (Cl. 242—25)

The present invention relates to winding apparatus. More particularly, the present invention relates to a winding apparatus of the type disclosed in co-pending application Ser. No. 428,074, filed May 6, 1954, now Patent No. 2,796,220 dated June 18, 1957, which concerns itself with a winding apparatus adapted to coil wire filaments or the like onto a spool which may, during the winding operation, either be held stationary, or be rotated.

It is an object of the present invention to provide such a winding apparatus in which the mechanism which enables the machine to operate with either a stationary spool or a rotating spool is an exceedingly simple one which is of sturdy construction and which may be built at very low cost.

It is another object of the present invention to provide a winding apparatus in which a simple manual operation is all that is required to transform the machine from a winding device in which the spool is stationary to a winding machine in which the spool is rotated.

With the above objects in view, the present invention mainly consists in that improvement in a winding apparatus which comprises rotatable spool means, rotatable winding means adapted to carry a filament for winding the same on the spool means, and motion transmitting means interconnecting the spool means and the winding means, which motion transmitting means include planetary gear means for holding the spool means stationary during rotation of the winding means and clutch means for coupling the spool means and the winding means for rotation with each other. The motion transmitting means are movable between two positions in one of which only the planetary gear means is operative and in the other of which only the clutch means is operative, so that the winding means may be rotated while the spool means is held stationary or be rotated together with the spool means.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing, in which:

Fig. 1 is a side elevational view, partly in section, of a winding apparatus according to the present invention; and

Fig. 2 is a detailed view of a guide roller mounting incorporated in the apparatus shown in Fig. 1.

Referring now to the drawing, there is shown a main support 30 which is adapted to carry a number of individual winding machines 31, one of them being shown in section on the left side of Fig. 1 and another being shown on the right side. It will be understood, however, that more than two individual machines may be arranged on the support, in which case the machines may be positioned one behind the other, as viewed in the drawing,

and with the machines alternately extending to the left and right. While only the left machine 31 will be described in detail, it will be understood that each winding machine may be of like construction.

5 The winding machine 31 includes a shaft 11 which is journaled in housing 32 by means of bearings 33. The shaft 11 extends outwardly of the housing, and carries a worm gear 34 which is freely rotatable relative to the shaft 11. The worm gear 34 is adapted to be 10 rotated by a worm 35 which extends throughout the entire length of the support 30 so as to be capable of rotating the worm gear of each winding machine. The shaft 11 also carries an axially displaceable sleeve 36 which is keyed to the shaft so as to be rotatable therewith. The 15 worm gear 34 and the sleeve 36 carry cooperating clutch components 37, 38, respectively, so that when the sleeve is moved rightwardly toward the worm gear these parts will be coupled to each other, thereby transmitting rotation of the worm 35 to the shaft 11 by way of the worm gear 34, the clutch components 37, 38 and the sleeve 36.

The shaft 11 carries a winding disk or drum 5 which is keyed to the shaft so as to be rotatable therewith. The disk 5 carries at its outer periphery a link 50 upon which a roller 40 is rotatably mounted. The link 50 is pivotable 25 between two positions, one of which is shown in solid lines and the other of which in dotted lines, so that different winding operations may be carried out.

The shaft 11 is formed with an axial bore 11a, and the wire filament or the like which is to be wound is 30 guided into this bore by means of guide rollers 41 and 42 arranged at one end of the shaft 11. A further guide roller 43 is arranged at the other end of the bore 11a for guiding the filament onto the roller 40, the mounting of this roller 40 being shown in greater detail in Fig. 2.

35 The shaft 11 also carries the hub 2 of a spool 3 upon which the filament wound by the winding disk 5 is coiled. This spool is arranged adjacent the disk 5 and is freely rotatable relative to the shaft 11.

As set forth above, the present invention concerns itself 40 with a winding machine in which the spool may be maintained stationary during the winding operation or in which the spool can be rotated together with the winding disk. Accordingly, suitable motion transmitting means are provided which interconnect the spool and the winding disk,

45 the motion transmitting means including a planetary gearing for holding the spool stationary during rotation of the winding disk as well as a clutch for coupling the spool and the winding disk for rotation with each other, the arrangement of the parts being such that any one time either the planetary gearing only or the clutch only will 50 be operative, so that at no time will both of these parts be operative.

The planetary gearing includes a pair of center or 55 sun gears 4 and 8 and a pair of planetary pinion gears 6 and 7 which are attached to a common axle 9, the latter being rotatably mounted on the winding disk 5. The center gear 8 is fixedly secured to the housing 32 and is permanently in mesh with the planetary pinion 7, whereas the center gear 4 is keyed to and therefore rotatable with a sleeve 1. This sleeve is mounted for free rotation upon the shaft 11 and is firmly attached to the hub 3, the parts 1, 2 and 3 together thus constituting a spool means.

In addition to being rotatable with the sleeve 1, the 60 center gear 4 is also axially movable relative thereto toward and away from the winding disk 5 between the two positions shown in solid and dotted lines, respectively. When the center gear 4 occupies the position shown in solid lines, the planetary gearing acts in such a manner as to hold the spool stationary during rotation of the shaft 11 together with the winding disk 5. This result is obtained inasmuch as the gear ratio between each cen-

center gear and its respective planetary pinion is the same so that the planetary pinion 6 simply revolves about the center gear 4 without causing rotation thereof. In this connection reference may be had to the above-mentioned co-pending application Ser. No. 428,074, filed May 6, 1954, now Patent No. 2,796,220 dated June 18, 1957.

The clutch for coupling the spool means 1, 2, 3 and the winding disk 5 for rotation with each other includes a pair of clutch components 44 and 45. The clutch component 44 is carried by the center gear 4 for rotation therewith as well as for axial movement therewith, and the clutch component 45 is carried by that part of the winding disk 5 toward and away from which the center gear 4 is axially movable. Thus, when the clutch components 44 and 45 are in engagement with each other, the winding disk 5 and the spool means 1, 2, 3 are coupled to each other for rotation with each other so that when the shaft 11 is rotated by the worm 35, the winding disk 5 and the spool means 1, 2, 3 both will be rotated.

The arrangement of the parts is such that the components 44 and 45 engage each other only when the center gear 4 is out of mesh with the planetary pinion 6. In other words, when the center gear 4 occupies the axial position shown in solid lines wherein it meshes with the planetary pinion 6, the clutch components 44 and 45 are spaced from each other and therefore do not couple the winding disk 5 and the spool means 1, 2, 3. Conversely, when the center gear 4 occupies the axial position shown in dotted lines wherein the components 44 and 45 engage each other, the center gear is axially displaced from the position in which it meshes with the planetary pinion 6. It will be seen, therefore, that at any one time either the planetary gearing 4, 6, 7, 8 or the clutch 44, 45 will be operative, it being impossible for both of these mechanisms to be operative at the same time.

The clutch 44, 45 may be of any suitable construction. In practice, it has been found that a claw clutch is particularly suitable.

Suitable moving means 10 are provided for moving the center gear 4 between its two axial positions whenever desired. These moving means may be manually operable and include a pair of rods 10a which extend through the spool hub 3 and are attached to the sleeve 1. A readily accessible handle 10b is attached to the rods 10a.

If desired, a suitable detent 46 may be provided for maintaining the center gear 4 in either of its two axial positions. The detent may be in the form of a spring-pressed plunger adapted to engage holes formed in one of the rods 10a, the location of the holes being so selected as to correspond to the proper axial positions of the center gear 4.

It will be understood that each of the elements described above, or two or more together, may also find a useful application in other types of winding apparatus differing from the types described above.

While the invention has been illustrated and described as embodied in a winding machine in which the position of the motion transmitting means is manually operable, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meanings and range of equivalence of the following claims.

What is claimed as new and desired to be secured by Letters Patent is:

1. In a winding apparatus, in combination, rotatable spool means; rotatable winding means adapted to carry a filament for winding the same on said spool means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, whereby said winding means may be rotated while said spool means is held stationary or be rotated together with said spool means.

2. In a winding apparatus, in combination, rotatable spool means; rotatable winding means adapted to carry a filament for winding the same on said spool means; driving means for rotating said winding means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, whereby said driving means may rotate said winding means while said spool means is held stationary or may rotate said winding means together with said spool means.

3. In a winding apparatus, in combination, rotatable spool means; rotatable winding means arranged adjacent said spool means and adapted to carry a filament for winding the same on said spool means; driving means for rotating said winding means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, whereby said driving means may rotate said winding means while said spool means is held stationary or may rotate said winding means together with said spool means.

4. In a winding apparatus, in combination, rotatable shaft means; driving means for rotating said shaft means; spool means mounted on said shaft means rotatably relative thereto, said spool means being adapted to have a filament wound thereon; winding means mounted on said shaft means for rotation therewith, said winding means being arranged adjacent said spool means and adapted to carry a filament for winding the same on said spool means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, whereby said driving means may rotate said shaft means together with said winding means while said spool means is held stationary or may rotate said shaft means together with both said winding means and said spool means.

5. In a winding apparatus, in combination, rotatable spool means; rotatable winding means arranged adjacent

said spool means and adapted to carry a filament for winding the same on said spool means; driving means for rotating said winding means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, said motion transmitting means including a center gear and a planetary pinion which are part of said planetary gear means, said center gear being rotatable with said spool means and axially movable relative thereto toward and away from said winding means, said motion transmitting means also including a pair of clutch components which are part of said clutch means, one of said clutch components being carried by said center gear for rotation therewith as well as for axial movement therewith and the other of said clutch components being carried by that part of said winding means toward and away from which said center gear is axially movable, said center gear and said clutch components being so constructed and arranged that when said motion transmitting means is in its one position, said center gear occupies an axial position wherein it meshes with said planetary pinion and wherein said clutch components are spaced from each other and are therefore out of engagement with each other, and that when said motion transmitting means is in its other position, said center gear occupies another axial position wherein it is out of mesh with said planetary pinion and wherein said clutch components are in engagement with each other, whereby said driving means may rotate said winding means while said spool means is held stationary or may rotate said winding means together with said spool means.

6. In a winding apparatus, in combination, rotatable spool means; rotatable winding means arranged adjacent said spool means and adapted to carry a filament for winding the same on said spool means; driving means for rotating said winding means; motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, said motion transmitting means including a center gear and a planetary pinion which are part of said planetary gear means, said center gear being rotatable with said spool means and axially movable relative thereto toward and away from said winding means, said motion transmitting means also including a pair of clutch components which are part of said clutch means, one of said clutch components being carried by said center gear for rotation therewith as well as for axial movement therewith and the other of said clutch components being carried by that part of said winding means toward and away from which said center gear is axially movable, said center gear and said clutch components being so constructed and arranged that when said motion transmitting means is in its one position, said center gear occupies an axial position wherein it meshes with said planetary pinion and wherein said clutch components are spaced from each other and are therefore out of engagement with each other, and that when said motion transmitting means is in its other position, said center gear occupies another axial position wherein it is out of mesh with said planetary pinion and wherein said clutch components are in engagement with each other; and means for moving said center gear between its two axial positions, whenever desired, whereby said driving means

may rotate said winding means while said spool means is held stationary or may rotate said winding means together with said spool means.

7. The combination defined in claim 6 wherein said means for moving said center gear between its two axial positions are manually operable.

8. The combination defined in claim 7, and detent means operatively associated with said means for moving said center gear between its two axial positions for maintaining the same in either of its two positions.

9. In a winding apparatus, in combination, rotatable shaft means; driving means for rotating said shaft means; spool means mounted on said shaft means rotatably relative thereto, said spool means being adapted to have a filament wound thereon; winding means mounted on said shaft means for rotation therewith, said winding means being arranged adjacent said spool means and adapted to carry a filament for winding the same on said spool means; and motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, said motion transmitting means including a center gear and a planetary pinion which are part of said planetary gear means, said center gear being rotatable with said spool means and axially movable relative thereto toward and away from said winding means, said motion transmitting means also including a pair of clutch components which are part of said clutch means, one of said clutch components being carried by said center gear for rotation therewith as well as for axial movement therewith and the other of said clutch components being carried by that part of said winding means toward and away from which said center gear is axially movable, said center gear and said clutch components being so constructed and arranged that when said motion transmitting means is in its one position, said center gear occupies an axial position wherein it meshes with said planetary pinion and wherein said clutch components are spaced from each other and are therefore out of engagement with each other, and that when said motion transmitting means is in its other position, said center gear occupies another axial position wherein it is out of mesh with said planetary pinion and wherein said clutch components are in engagement with each other, whereby said driving means may rotate said shaft means together with said winding means while said spool means is held stationary or may rotate said shaft means together with both said winding means and said spool means.

10. In a winding apparatus, in combination, rotatable shaft means; driving means for rotating said shaft means; spool means mounted on said shaft means rotatably relative thereto, said spool means being adapted to have a filament wound thereon; winding means mounted on said shaft means for rotation therewith, said winding means being arranged adjacent said spool means and adapted to carry a filament for winding the same on said spool means; motion transmitting means interconnecting said spool means and said winding means and including planetary gear means for holding said spool means stationary during rotation of said winding means and clutch means for coupling said spool means and said winding means for rotation with each other, said motion transmitting means being movable between two positions in one of which only said planetary gear means is operative and in the other of which only said clutch means is operative, said motion transmitting means including a center gear and a planetary pinion which are part of said planetary gear means, said center gear being rotatable with said spool means and axially movable relative ther-

7 to toward and away from said winding means, said motion transmitting means also including a pair of clutch components which are part of said clutch means, one of said clutch components being carried by said center gear for rotation therewith as well as for axial movement therewith and the other of said clutch components being carried by that part of said winding means toward and away from which said center gear is axially movable, said center gear and said clutch components being so constructed and arranged that when said motion transmitting means is in its one position, said center gear occupies an axial position wherein it meshes with said planetary pinion and wherein said clutch components are spaced from each other and are therefore out of engagement with each other, and that when said motion transmitting means is in its other position, said center gear

10

15

occupies another axial position wherein it is out of mesh with said planetary pinion and wherein said clutch components are in engagement with each other; and means for moving said center gear between its two axial positions, whenever desired, whereby said driving means may rotate said shaft means together with said winding means while said spool means is held stationary or may rotate said shaft means together with both said winding means and said spool means.
